[57] CLAIM

The ornamental design for a remote control housing for a vehicle immobilizer/anti-theft system, as shown and described.

DESCRIPTION

FIG. 1 is a top view of a remote control housing for a vehicle immobilizer/anti-theft system showing our new design;

FIG. 2 is a side view thereof, the opposite side view being the same; and,

FIG. 3 is a bottom view thereof.

FIG. 1

FIG. 2

FIG. 3
